UNITED STATES PATENT OFFICE

2,426,190

MECHANICAL TIME FUSE

Cecil C. Fawcett, Philadelphia, Pa.

Application December 15, 1939, Serial No. 389,416

2 Claims. (Cl. 102—79)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a firing pin actuated fuse and more particularly to a safety barrier for preventing ignition of the fuse primer upon premature or accidental release of the firing pin.

While the invention has particular reference to a barrier for a firing pin, it is not limited to this sole function; but may also be of utility in obstructing or blocking any passage in any suitable fuse where it is desired to block such passage until a predetermined time in order to render the fuse safe.

It is an object of this invention to provide a positive acting firing pin barrier automatically inoperative upon firing a projectile armed with a fuse provided therewith and which is simple in construction, economical in manufacture and so arranged as to lend itself to compact adaptation in the fuse organization.

The specific nature of the invention as well as other objects and advantages thereof will clearly appear from a description of a preferred embodiment as shown in the accompanying drawings in which:

Fig. 1 is a horizontal sectional view through a fuse provided with a firing pin barrier embodying the invention;

Fig. 2 is a sectional view taken on the line 2—2 of Fig. 1;

Fig. 3 is a plan view on an enlarged scale of a lever used in the firing pin barrier; and,

Fig. 4 is an end elevation of the structure shown in Fig. 3.

Referring now to the drawings wherein like characters are used to indicate like parts throughout the views there is shown in Fig. 1 a supporting plate or similar frame member 10 comprising one of a plurality of similar superimposed members constituting the framework for supporting and housing the fuse components.

The plate 10 is eccentrically recessed as indicated at 11 within which is disposed the safety barrier of this invention generally indicated at 12. Radially outward of the plate 10 and within the recess 11 the plate is formed with a passage 13 through which the firing pin 14 may project to impinge upon and ignite the primer 15 in operative communication with an explosive train of the fuse.

The safety barrier 12 comprises a pair of identical cranked safety levers 16 mounted at the point of intersection of their arms 17 and 18 on

2

a pivot pin 19, whose center is located on the radial line of member 10 passing through the center of passage 13, in such manner that the arms 17 will normally lie in registering relation covering passage 13 while the arms 18 will be disposed in diverging relation to form the scissors-like arrangement shown. To restrain the levers 16 to their normal position as shown in Fig. 1, a stop pin 20 is disposed between the arms 18 of the levers on the radial line passing through the centers of pin 19 and passage 13 and resilient elements 21, which may be in the form of flat springs suitably anchored at one end are so disposed as to have their free ends engage and urge the arms 18 of the levers 16 into abutting relation with the stop pin 20. Conveniently in the embodiment of the invention illustrated the stop pin 20 is located at the center of member 10.

For a purpose hereinafter made clear the free ends of the arms 18 of the levers 16 are provided with centrifugal weights 22. While these weights are shown confronting each other in Fig. 1 it will of course be understood that in forming the levers the weights are all applied thereon in the same manner to facilitate production.

In operation the levers 16 will occupy a normal position as shown in Fig. 1 in which position the arm 17 of each lever will cover the passage 13 in such manner as to prevent the firing pin 14 from striking the primer 15.

If the fuse bearing this barrier receive a shock from the right side as viewed in Fig. 1 the rightmost lever 16 will pivot about its pivot pin 19 against the cooperating spring 21 but the lever 16 on the left will be restrained from moving by the stop pin 20 and thereby continue to block the passage 13 whereby the firing pin 14 will be unable to strike the primer 15 in the event that the shock also released the firing pin. The reverse action will take place if the fuse receives a shock from its left side so in any situation the two levers 16 arranged as herein disclosed will be effective to maintain the fuse safe until predetermined operation is desired.

When a fuse provided with the barrier of this invention is used to arm a projectile the rotation imparted to the projectile in firing will be sufficient through the centrifugal force developed to cause both weighted arms 18 to swing about their pivot 19 and in turn swing the arms 17 to uncover passage 13. After the lapse of a predetermined time the firing pin 14 will be released and is then free to impinge upon and ignite the primer 15.

Having now particularly described what is at

present considered a preferred embodiment of this invention I claim and desire to secure by U. S. Letters Patent:

1. In a fuse in combination, a supporting member formed with a passage therethrough, a pair of superimposed cranked levers coaxially pivoted on the supporting member intermediate their end portions with two of the arms of said levers normally disposed in registering relation blocking said passage and the other two arms of said levers arranged in diverging relation, a stop pin disposed between said diverging arms and resilient means urging the diverging arms into abutting relation with the stop pin to maintain said arms blocking the passage in normal registering relation.

2. In a fuse in combination, a circular supporting member eccentrically recessed on one face and formed with a passage therethrough in the recess on a radial line, a pivot pin mounted on the member within the recess and on said radial line, a pair of superimposed identical cranked levers mounted on the pivot pin intermediate their end portions and adapted to have two arms brought into registering relation covering said

passage and the other two arms diverging from said pivot pin, weights on the end portions of the diverging arms of the levers, a stop pin mounted on the member within the recess on said radial line intermediate the diverging arms of the levers and adapted to be abutted by the diverging arms when the other arms of the levers are in registering relation covering said passage and resilient means normally urging the diverging arms into abutment with said stop pin.

CECIL C. FAWCETT.
